UNITED STATES PATENT OFFICE.

EMIL A. MEYER, OF SPRINGFIELD, OHIO, ASSIGNOR, BY MESNE ASSIGNMENTS, TO ROBBINS & MYERS, INC., OF SPRINGFIELD, OHIO, A CORPORATION OF OHIO.

CIRCUIT MAKER AND BREAKER.

Application filed May 24, 1927. Serial No. 193,907.

This invention relates to a circuit maker and breaker of the type which employs an auxiliary shunt having arcing contacts which open later than the main contacts.

5 The object of my invention is to provide for a quick break of the shunt contacts; a more specific object in this connection being to provide an arrangement in which both contacts of the shunt are movable, with one 10 of the contacts movable sidewise to bend and break the arc.

In the accompanying drawings:

Fig. 1 is a side elevation of a switch embodying my improvements.

15 Fig. 2 is an elevation of the opposite side from that shown in Fig. 1.

Fig. 3 is a top plan view.

Fig. 4 is a top plan view of a portion of the same.

20 Fig. 5 is an enlarged side elevation of a portion of the device partly broken away and shown in section.

Referring to the drawings, 1 represents a base of insulating material upon which the 25 parts are mounted. The main stationary contact is indicated at 2 and the movable contact at 3. The stationary contact is in the form of an inclined plate, bent to form a foot 2' which is secured to the base. The 30 movable contact member 3 is formed of a series of spring members which are secured to a lever 4 pivotally mounted at the upper ends of standards 5 which are secured to the base 1. A coil spring 6 fastened at one 35 end to the arm 4' of the lever and at the other end to the base tends normally to hold the main switch member in the open position shown in Fig. 1; a stop 7 cooperating with the free end of the lever 4 to limit its opening movement. One of the arcing contacts is shown at 8, this contact being mounted 40 on the free end of a spring 3' which forms one of the series of springs 3 of the main contact member but is extended outwardly 45 beyond the free end of the same. The other arcing contact is shown at 9, this contact being mounted on the end of an arm 10 fixed to a shaft 11 mounted to rotate in brackets 12, supported on the foot 2'.

50 Means are provided for rotating the shaft

11 upon each opening and closing movement of the main contact 3 so that when the main switch is in the open position shown in Fig. 1 the contact 9 will be rocked to the position shown in full lines in that figure, 55 while when the main switch is in the closed position shown in Fig. 2 the arcing contacts 8 and 9 will also be in closed position as shown in that figure with the upper end of the contact plate 2 acting as a stop for 60 the arcing contact 9. The lever 4 which carries the main movable contact is connected with a shaft 13 which is mounted to rotate in the brackets 5. Connected to one end of this shaft 13 is an arm 14 to the free 65 end of which is connected a link 15 through the medium of a coil spring 16, the link 15 being preferably provided with a socket which houses the spring as shown in Fig. 5. The link 15 has connected to one end 70 thereof a second link 17, the other end of which is pivotally connected with an eccentric pin 18 projecting laterally from a disk 19 which is mounted to rotate on a stud 20 supported by one of the brackets 12. The 75 disk 19 has a gear segment 21 meshing with the pinion 22 fast to the shaft 11.

The operation is as follows: When the main switch members are closed by operating the lever 4, or otherwise, rocking of the shaft 13 rocks the arm 14, which, through the connections described, rocks the shaft 11 so as to swing the arm 10 and its contact 9 to a position in line with the contact 8, the upper portion of the inclined stationary contact 2 acting as a stop for the contact 9. The arcing contacts 8 and 9 then close and make the circuit prior to the main contacts, the spring connection 16 with the arm 14 allowing for a further movement of the lever 4 and main 85 contact 3 to close the circuit through the main contacts, the spring arcing contact member 3' yielding to allow for this additional movement. When the lever 4 is released, the spring 6 acts to open the circuit by rocking the lever to the position shown in Fig. 1, and when this movement of the lever takes place the circuit is first broken through the main contacts by reason of the fact that the arm 14 90 must move a limited distance before it strikes 95 the base 1. The lever 4 is held in the position shown in Fig. 1 by the spring 6 until the main contacts 2 and 3 are closed, the lever 4 then being held in the closed position by the coil spring 16 until the main contacts 2 and 3 are opened, the lever 4 then being held in the open position by the coil spring 16. The coil spring 16 is so arranged that it will not 100

the end of the link 15. When the arm 14 engages the link 15 the shaft 11 is rocked in the opposite direction and the arm 10 and its arcing contact 9 swings sidewise. At the same time the free end of the main contact 3 engages the outer end of the spring 3' and carries the contact 8 with it during the further opening movement of the main contact 3. Thus, the circuit is broken through the arcing contacts by a movement of both contacts, which furnishes a quick break, and, further, by reason of the fact that the arcing contact 9 is swung sidewise, this acts to bend and break the arc.

15 The particular device shown in the drawings is for use in connection with time controlled switches, the lever being operated to close the switch by a part indicated in dotted lines at 23 which is operated by clock mechanism, or by a clock controlled motor, this part 23 being withdrawn after the switch has been moved to closing position. It is to be understood however that the improvements are equally applicable to electric switches 25 used in other connections.

Having thus described my invention, I claim:

1. In a circuit maker and breaker, a pair of main contacts, one at least of which is movable, and a pair of shunt arcing contacts, one at least of which is supported independently of the main contacts, both of which are simultaneously movable to break the circuit after the breaking of said main contacts.

35 2. In a circuit maker and breaker, a pair of main contacts one at least of which is movable, and a pair of shunt arcing contacts, one at least of which is supported independently of the main contacts, both of which are simultaneously movable to break the circuit after the breaking of said main contacts, one of said arcing contacts being pivoted so as to move on the arc of a small circle.

45 3. In a circuit maker and breaker, a pair of main contacts one at least of which is movable, and a pair of shunt arcing contacts, one of said arcing contacts being connected with a main movable contact and movable thereby to breaking position after the main contacts 50 have broken, the other arcing contact being supported independently of said main contacts, and means for moving the last mentioned arcing contact to breaking position simultaneously with the companion arcing contact.

4. In a circuit maker and breaker, a pair of main contacts, one at least of which is movable, an arcing contact carried by a main movable contact, a second arcing contact supported independently of said main contact having an operative connection with said main movable contact so as to be simultaneously movable to breaking position with the companion arcing contact, said main movable 65 contact being capable of a limited movement

to break with its companion main contact prior to causing the breaking of the arcing contact.

5. In a circuit maker and breaker, a main stationary contact, a main movable contact, 70 an arcing contact carried by said main movable contact, a second arcing contact mounted independently of said main contacts, together with means for moving the same to and from said first mentioned arcing contact simultaneously with the movement thereof, said main movable contact being capable of a limited movement relatively to the arcing contact carried thereby.

6. In a circuit maker and breaker, a pair 80 of main contacts, means for moving at least one of said contacts to open position, a pair of shunt arcing contacts, one at least of which is supported independently of said main contacts, both of said shunt arcing contacts being simultaneously movable by said means to break the circuit after the breaking of the main contacts.

7. In a circuit maker and breaker, a pair 90 of main switch members, one at least of which is movable, and a pair of shunt arcing contact members, both of which have a connection with the main movable switch member to be moved simultaneously thereby to open the circuit after the main switch members have 95 broken, the connection between said main movable switch member and one of said shunt arcing members consisting of a rock shaft to which said arcing member is connected, a rocker arm operatively connected with the 100 main movable switch member, and operative connections between said arm and shaft, the connections being such as to allow a limited movement of said arm relatively to said shaft.

8. In a circuit maker and breaker, a pair 105 of main switch members, one at least of which is movable, and a pair of shunt arcing contact members, both of which have a connection with the main movable switch member to be moved simultaneously thereby to open 110 the circuit after the main switch members have broken, the connection between said main movable switch member and one of said shunt arcing members consisting of a rock shaft to which said arcing member is connected, a pinion on said rock shaft, a pivoted gear segment meshing with said pinion, a rocker arm operatively connected with the main movable switch member, and a link connection eccentrically connected with said gear 115 segment and having a connection with said rocker arm such as to permit limited movement of said rocker arm relatively thereto.

9. In a circuit maker and breaker, a pair of main switch members, one of which is movable and the other stationary, a pair of shunt arcing contact members, one of said arcing contact members having a connection with the main movable member such as to allow 125 said main member to have a limited move- 130

ment relatively thereto, the other of said arcng contact members being pivotally mounted to swing on the short arc of a circle with the stationary main contact member act-
5 ing as a stop to limit its movement in one direction, a rocker arm having an operative connection with the main movable switch member, and an operative connection between said arm and said last mentioned arcng contact member constructed to permit said rocker 10 arm to have a limited movement relatively to said arcng member.

In testimony whereof, I have hereunto set my hand this 19th day of May, 1927.

EMIL A. MEYER.
